UNITED STATES PATENT OFFICE.

WILLIAM HOMER COLGATE, OF LARCHMONT, NEW YORK.

MATCH-BOOK HOLDER.

Application filed May 5, 1925. Serial No. 28,107.

This invention relates to holders or temporary covers for the reception and protection of match books such as are commonly sold and used in great numbers, consisting 5 of several short strips of paper matches secured together in a book or package with a paper cover and an ignition strip. The object of the invention is to produce a holder which can be manufactured at low cost, particularly as compared with folders made of 10 leather or metal, shall be capable of continued use with a succession of match books, and shall have an attractive appearance with, it may be, a personal touch. The 15 holder is made of a multi-ply stock, such as paper or fabric, the outer ply being ornate, while the inner ply or plies is or are of suitable stock to give the necessary strength, 20 stiffness and body. The invention is particularly concerned with the construction of a holder of such stock, the construction being of such a character as to permit the ready 25 removal of an exhausted match book and the replacement of a fresh match book. The invention will be more fully described hereinafter with reference to the accompanying drawing in which it is illustrated and in which—

Figure 1 is a view in elevation of an open 30 holder embodying the invention with a match book applied thereto.

Figure 2 is a view of the same in longitudinal section.

Figure 3 is a view in elevation of a closed 35 holder.

Figures 4, 5, 6 and 7 are detail views in elevation and on a smaller scale illustrating successive features of construction.

Figures 8 and 9 are views similar respectively to Figures 1 and 2 but showing a slightly different embodiment of the invention and with the match book omitted.

It will be understood that the stock of which the improved holder is formed, can be made of two or more plies, which are secured together by an adhesive usually under considerable pressure. In the embodiments of the invention illustrated in the drawing, the stock is shown as made up of an outer 45 ply *a*, as of paper, which is ornamental and more or less distinctive and personal in color or design, and an inner ply *b*, which is of such material as may be necessary to give the requisite strength and stiffness. The two 50 plies, it will be understood, are secured together by an adhesive. As shown, the com-

pleted holder is generally rectangular in outline, with an interlocking tongue *b*¹ at one end and a co-acting slit *b*² at the other end.

In Figures 1 and 2 the slit *b*² is so placed 60 with reference to the ignition strip *c*¹ of the match book *c* that the tongue *b*¹ overlaps the ignition strips, while in the construction shown in Figure 8 the lower portion of the holder is somewhat elongated, as compared 65 with the holder shown in Figures 1 and 2, so that the slit *b*², when the holder is closed, shall stand in such relation to the ignition strip as to permit the tongue *b*¹ to be slipped under the ignition 70 strip when the holder is closed. The transverse broken lines of Figures 1, 4, 5 and 8 indicate the lines on which the holder is flexed when closed. In accordance with the present invention the stiff paper back *c*² of 75 the match book is engaged with the holder *a*—*b* in a pocket formed as a part of the holder and the problem, in the present invention, has been to provide such a pocket without increasing greatly the cost of the 80 holder. To this end the inner ply is slotted transversely as at *b*³ in Figure 5, before the two plies are secured together and provision is made whereby the two plies shall be prevented from adhering together for a space 85 sufficient to permit the introduction of the tongue *c*² of the match book. To this end there is provided a strip *d* of paper or fabric which is inserted through the slit *b*³ before the two plies are secured together and serves 90 to prevent the adhesion of the two plies over an area sufficient to form a pocket for the reception of the back *c*² of the match book, as indicated in Figures 2 and 9. The end of the guard strip *d* is preferably left projecting 95 from the slit at the inner face of the holder, as indicated at *d*¹, to form a guide tab to facilitate the introduction of the tongue or back *c*² of the match book. If the adhesive is applied to the approximate surface 100 of only one ply, the guard strip may be only of such size as shall be sufficient to form the desired pocket, its surface adhering on one side to the adhesive coated ply and being free only at its other face from the non-coated ply. However, it is generally preferable 105 to make the guard strip of such length that it can be folded, as shown in Figures 2, 6 and 9, so that the pocket shall be formed between its two members even if the approximate surfaces of both plies are coated 110 with adhesive, as may be the case. There is

thus formed, in the holder, in one way or the other, a pocket which is free from adhesive and into which the tongue or back of the match book can be slipped readily, being guided by the projecting tab d^1 of the guard strip.

It will be understood that various changes in details of construction can be made to suit different conditions of use and that, except 10 as pointed out in the claims, the invention is not restricted to the particular construction shown and described herein.

I claim as my invention:

1. A multi-ply holder for match books 15 consisting of several plies secured together by adhesive and having a slit through the inner ply and a guard strip between the plies to prevent adhesion thereof and form a pocket communicating with the slit to receive the tongue of a match book.

2. A multi-ply holder for match books 20

consisting of several plies secured together by adhesive and having a slit through the inner ply and a guard strip between the plies to prevent adhesion thereof and form 25 a pocket communicating with the slit to receive the tongue of a match book, said guard strip having an end projecting externally through the ply to form a guide tab.

3. A multi-ply holder for match books 30 consisting of several plies secured together by adhesive and having a slit through the inner ply and a guard strip between the plies to prevent adhesion thereof and form 35 a pocket communicating with the slit to receive the tongue of a match book, said guard strip being doubled upon itself for contact with the adhesive coated surfaces of both plies.

This specification signed this 1st day of May A. D. 1925.

WILLIAM HOMER COLGATE.
